UNITED STATES PATENT OFFICE.

HORATIO G. GILLMOR, OF WASHINGTON, DISTRICT OF COLUMBIA.

RAIL-ANCHOR.

1,207,742.

Specification of Letters Patent. Patented Dec. 12, 1916.

Application filed April 2, 1915. Serial No. 18,725.

To all whom it may concern:

Be it known that I, HORATIO G. GILLMOR, a citizen of the United States, and resident of Washington, in the District of Columbia, have invented a new and useful Improvement 5 in Rail-Anchors, of which the following is a specification, accompanied by drawings.

This invention relates to devices known 10 as rail anchors, rail stays or anticreepers and one of its objects is to form a simple device which will prevent longitudinal movement of the rails of railways.

Another object of the invention is to provide 15 means for securing the device upon the rail in such manner that its hold shall not be lost by a reverse movement of the rail or by the vibrations to which the rail is subject.

To the accomplishment of these objects and such others as may hereinafter appear, as will be readily understood by those skilled in the art, the invention comprises a rail anchor, embodying features of construction, the combination of elements and arrangement of parts having the general mode 20 of operation as hereinafter described and claimed.

The preferred embodiment of the invention 25 is shown in the accompanying drawings, in which:—

Figures 1, 2 and 3 are, respectively, a plan view, a side elevation and a transverse elevation showing the device in operative 30 position on the rail. Figs. 4 and 5 are, respectively, a plan view and a transverse elevation showing two positions of the device while being placed upon the rail. Fig. 35 6 is a section through the rail and the device 40 at the plane indicated by the line X X in Fig. 1.

Similar letters apply to similar parts throughout the several views.

In the embodiment of the invention illustrated 45 in the drawings A is the rail and B the rail anchor, constructed with a tie abutting portion C which engages with a face of the tie D. The anchor B is constructed with shoulders E and F arranged to engage 50 the edges of the rail base flange and a jaw G formed by the projecting rib H. For additional strength to the shoulder F and the jaw G the web I is provided. The opposite end of the anchor B is formed with 55 an arm K arranged to engage the upper

surface of the rail base flange above the tie when the tie abutting portion of the anchor C is engaging the vertical face of the tie as shown in the Figs. 1, 2 and 3. To give stiffness to this arm K the ribs or flanges 60 L and M are provided. The tie abutting portion C is provided with a stiffening web N and the shoulder E is strengthened by the web or flange O.

To place the device in position on the rail 65 it is brought below the rail with the arm K just engaging the top of the rail base flange and moved to such an angle that the end of the rib H, forming the jaw G, can be raised by the edge of the rail base flange 70 at the side of the rail opposite to the arm K. This position is illustrated in Fig. 4. In this position the shoulder E is below the rail base flange as shown. The device is now moved transverse to the rail and at the 75 same time moved angularly in relation to the rail until the jaw G has the edge of the rail base flange entered as shown in Fig. 5. In this position the shoulder E is still below the rail bottom and the body of the device 80 B is subject to some torsion. If the device be now forced to position by further rotation of B in relation to the rail and by forcing the rail edge into the jaw G, which necessary movements may be produced by 85 tapping I transversely in relation to the rail and O longitudinally of the rail the position shown in Fig. 1 will be reached and in this position the face of the shoulder E will clear 90 the edge of the rail base flange and the torsion of the body of B will cause this shoulder to engage the face of the shoulder E with the edge of the rail base flange. When the device B is in this position the opposite 95 edges of the rail base flange are engaged by the shoulders E and F as shown in the section Fig. 6.

The direction in which the rail tends to move is indicated by the arrow in Fig. 1. This movement will be referred to as the 100 forward movement of the rail. As the rail moves forward it carries with it the device B until the tie abutting portion C comes into contact with the tie D. The first effect of any further tendency of the rail to move 105 forward is to impart a torsional movement to B the arm K of which is engaging the upper surface of the rail base flange forward of the tie abutting portion C, so that if the shoulder E is not already in full en- 110

gagement with the edge of the rail base flange the torsional movement of B produced by this forward movement of the rail with C in contact with the tie D will complete the engagement of the shoulder E with the edge of the rail base flange.

The rail base flange at the side opposite to C and K is gripped in the jaw G and any further tendency to forward movement 10 of the rail will carry forward, with the rail A, the jaw G altering slightly the angle of B to the rail A. This angular movement of B in relation to A will cause the rail edges to be more firmly gripped between 15 the shoulders E and F and thus automatically increase the resistance which the device opposes to further movement of the rail.

Should the rail, through change in temperature or other cause, move in the backward or reverse direction the device B will be carried with the rail in this reverse direction and the stress on the forward face of C would be released. It will be readily understood that even when this is the case, 25 the engagement of the shoulders E and F with the base flange edges will prevent the vibration of the rail from loosening or disengaging the device upon the rail. Moreover, should C be held against this backward or reverse movement the jaw G would be carried backward by the rail and B moved angularly upon the rail. The effect of this angular movement would be to 30 tighten the device and further prevent its being detached from the rail.

Obviously some features of the invention may be used without others and the invention may be embodied in widely varying forms within the scope of the artisan.

40 Therefore without limiting the invention to the construction shown and described or enumerating equivalents, I claim and desire to secure by Letters Patent:—

1. A device for preventing the creeping of rails comprising a cross bar extending transversely under the rail and having integral shoulders thereon adapted to bear against and grip opposite edges of the rail base flange and provided at one end with an integral jaw adapted to engage the rail base flange and at the other end with an integral tie-engaging portion.

2. An anticreeper, comprising a cross bar having integral rail base engaging portions upon its two ends adapted to engage the top and bottom of the rail base at opposite sides of the rail and an integral rail edge engaging shoulder adapted automatically to engage the edge of the rail base when said anticreeper is forced into position and to lock said anticreeper upon the rail base.

3. A rail anchor comprising a device arranged for transverse application to a rail base and having at one end an integral jaw 65 and an integral rail base edge engaging

shoulder and at the other end thereof an integral arm adapted to engage the upper surface of the rail base flange and an integral shoulder adapted to engage the edge of the rail base flange to lock said device 70 upon the rail base.

4. A device for preventing the creeping of rails comprising a cross bar having at one end an integral jaw adapted to engage the top and bottom of the rail base and an integral shoulder adapted to engage the rail edge and at the other end an integral tie-engaging portion an integral arm adapted to engage the upper surface of the rail base at 75 one side of said tie-engaging portion and an integral shoulder adapted to engage the edge of the rail base at the other side of said tie-engaging portion. 80

5. A rail stay comprising a cross bar having base edge engaging portions upon its ends, a rail base engaging jaw at one end and an arm adapted to engage the upper surface of the rail base at the other end, the whole adapted to be placed in position upon the rail by horizontal angular movement in 90 relation to the rail and to be locked upon the rail by the engagement of the base edge engaging portions with opposite edges of the rail base.

6. A rail anchor comprising a cross bar 95 having integral rail base edge engaging portions upon its ends, an integral flange engaging jaw at one end and an integral angularly disposed arm at the other end adapted to engage the upper surface of the rail base 100 flange.

7. An anticreeper comprising a transversely disposed body having at one end an integral jaw and rail base edge engaging shoulder and at the other end an integral 105 tie-engaging portion, an integral arm adapted to engage the upper surface of the rail base and a shoulder adapted to engage the edge of the rail base to lock said anticreeper on the rail.

8. A rail anchor comprising a cross bar having at one end an integral tie abutting portion an upwardly extending overturned arm integral with said bar and adapted to engage the upper surface of the rail base 115 flange at one side of said tie abutting portion and an integral shoulder adapted to engage the edge of the rail base flange at the other side of said tie abutting portion and rail base engaging means at the free end of 120 said bar.

9. An anticreeper comprising a cross bar with an integral tie-engaging flange, an integral rail base edge engaging portion at the other end of said bar, an integral rail 125 base engaging hook and an integral rail base edge engaging shoulder at opposite sides of said tie-engaging flange.

10. A rail stay comprising a transverse bar constructed with a tie engaging flange 130

at one end of said bar and integral rail base engaging hooks at both ends of said bar and a shoulder integral with said bar at one end thereof adapted automatically to engage 5 the edge of the rail base flange when said stay is forced into position to lock said stay in place upon the rail base.

11. A rail anchor comprising a cross bar having at one end an integral tie engaging 10 portion, an angularly disposed arm adapted to engage the upper surface of the rail base forward of said tie-engaging portion and a shoulder adapted to engage the rail edge back of said tie-engaging portion and, at 15 the other end of said bar a rail base edge engaging shoulder integral with said bar.

12. An anticreeper, comprising a cross bar provided with a jaw at one end and an arm, a shoulder and a tie-abutting portion at the 20 other end thereof the whole being so proportioned that when said jaw and said arm are engaging the rail base at opposite sides of the rail by angular movement of said cross bar upon the rail base in one direction 25 said shoulder may be brought into such engagement with the rail base edge as to prevent reverse angular movement of said cross bar upon the rail base.

13. A rail stay comprising a cross bar 30 constructed with rail base engaging hooks upon the two ends thereof and a shoulder at one end thereof all so arranged that when said hooks are applied to upper surfaces of the rail base at opposite sides of the rail 35 said shoulder may be sprung into engagement with the edge of the rail base so as to

hold said stay in operative engagement with the rail.

14. A device for preventing the creeping 40 of rails comprising a strap provided, at one end, with a tie-engaging flange, an arm adapted to engage the upper surface of the rail base forward of said flange and a shoulder back of said flange and provided at 45 the other end of said strap with a jaw and shoulders all so proportioned and arranged that, when said arm and jaw engage the upper surfaces of the rail base at opposite sides of the rail said shoulders may be sprung into engagement with the edges of 50 the rail base and the device so locked upon the rail base.

15. A rail stay comprising a strap for 55 transverse application to a rail base provided with a jaw at one end and an arm and a shoulder at the other end thereof so proportioned and arranged that when said arm is applied to the upper surface of the rail base at one side of the rail and said jaw is in engagement with the rail base at the 60 other side of the rail angular movement of said strap on the rail base in one direction will cause said shoulder to engage the edge of the rail base and lock said strap in operative position on the rail by preventing reverse angular movement of said strap on 65 the rail base.
